(57) **CLAIM**

I claim the ornamental design for a deck post, as shown and described.

DESCRIPTION

FIG. 1 is a foreshortened perspective view of the deck post of my design;

FIG. 2 is a foreshortened side elevational view thereof, the opposite side elevational view being a mirror image thereof; FIG. 3 is a foreshortened front elevational view thereof, the rear elevational view being a mirror image thereof;

FIG. 4 is a top plan view thereof; and,

FIG. 5 is a bottom plan view thereof.
